UNITED STATES PATENT OFFICE

92,155

DESIGN FOR A LACE CAPE OR SIMILAR ARTICLE

Roman Sutter, Grantwood, N. J.

Application March 14, 1934, Serial No. 51,040

Term of patent 3½ years

To all whom it may concern:

Be it known that I, ROMAN SUTTER, a citizen of the United States, residing at 452 Lawton Avenue, Grantwood, Bergen County, State of New Jersey, have invented a new, original, and ornamental Design for a Lace Cape or Similar Article, of which the following is a specification, reference being had to the accompanying drawing, forming part thereof:

Figure 1 is a plan view of the cape showing my new design and the dot and dash lines indicate the center of the cape, it being understood that the other half is identical with the half illustrated. The tie portion of the cape has been broken off it being understood that the ornamentation thereon is continuous.

I claim

The ornamental design for a lace cape or similar article, as shown and described.

ROMAN SUTTER.
